US0D1041245S

(12) **United States Design Patent** (10) **Patent No.:** **US D1,041,245 S**
(45) **Date of Patent:** **** Sep. 10, 2024**

(54) **BOTTLE LID**

(71) Applicant: **Everich And Tomic Housewares Co., Ltd**, ZheJiang (CN)

(72) Inventor: **Huajun Yao**, Hangzhou (CN)

(**) Term: **15 Years**

(21) Appl. No.: **29/858,168**

(22) Filed: **Oct. 28, 2022**

(30) **Foreign Application Priority Data**

May 18, 2022 (CN) 202230294916.8

(51) **LOC (14) Cl.** **07-01**

(52) **U.S. Cl.**

USPC **D7/392.1; D7/396.2**

(58) **Field of Classification Search**

USPC D7/387, 391, 392, 392.1, 396.2, 396.3, D7/509, 510, 511, 512, 528, 533, 534, D7/536, 601, 602, 619.1, 619.2, 620, 621, D7/622, 623, 624.1, 624.2, 624.3, 625, D7/628, 629, 630, 709, 710, 529, 532, D7/608, 514, 393, 300-322; D9/435, D9/436, 440, 441, 443, 445, 447, 454, D9/449, 453, 516, 450, 439; D3/201, D3/202; D24/127

(57) **CLAIM**

The ornamental design for a bottle lid, as shown and described.

DESCRIPTION

FIG. 1 is a front and top perspective view of a bottle lid, showing my new design;
FIG. 2 is a rear and top perspective view thereof;
FIG. 3 is a rear and bottom perspective view thereof;
FIG. 4 is a front elevation view thereof;
FIG. 5 is a rear elevation view thereof;
FIG. 6 is a left side elevation view thereof;
FIG. 7 is a right side elevation view thereof;
FIG. 8 is a top plan view thereof; and,
FIG. 9 is a bottom plan view thereof.

(Continued)

The broken lines in the figures illustrate portions of the bottle lid that form no part of the claimed design.

1 Claim, 9 Drawing Sheets
